DESIGN FOR A METER FACE

Lawrence A. Blazey, Cleveland, Ohio, assignor to
Benjamin F. W. Heyer, Tenafly, N. J.

Application November 14, 1939, Serial No. 88,255

Term of patent 7 years

To all whom it may concern:

Be it known that I, Lawrence A. Blazey, a citizen of the United States, residing at Cleveland, in the county of Cuyahoga and State of Ohio, have invented a new, original, and ornamental Design for a Meter Face, of which the following is a specification, reference being had to the drawing accompanying this application and forming part thereof.

In the drawing:

Figure 1 is a front elevation; and

Figure 2 is a view in perspective of a meter face showing my new design.

I claim:

The ornamental design for a meter face, as shown.

LAWRENCE A. BLAZEY.
